UNITED STATES PATENT OFFICE.

GEORGE B. WEBB, OF WESTFIELD, NEW JERSEY, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 703,866, dated July 1, 1902.

Original application filed March 2, 1897, Serial No. 625,724. Divided and this application filed February 21, 1898. Serial No. 671,036. (No model.)

To all whom it may concern:

Be it known that I, GEORGE B. WEBB, a citizen of the United States, and a resident of Westfield, in the county of Union and State 5 of New Jersey, have invented certain new and useful Improvements in Type-Writing Machines, of which the following is a specification.

This application is filed as a division of my 10 application filed March 2, 1897, Serial No. 625,724, patented February 22, 1898, No. 599,429, and relates more particularly to the construction and mode of mounting of the paper-carriage.

15 My main objects are to provide a light and true running carriage and one in which the weight of the carriage is supported upon roller-bearings; and my improvements consist in the various features of construction 20 and combination of devices hereinafter more fully described, and particularly pointed out in the appended claims.

In the accompanying drawings, Figure 1 is 25 a plan view of enough of a type-writing machine to exhibit my invention. Fig. 2 is a vertical cross-section thereof, taken at the line *x x* of Fig. 1, but showing the top plate of the machine added; and Fig. 3 is a detailed cross-section showing a modification of my 30 invention, in which antifriction-balls are substituted for the antifriction-rolls shown in the main views.

In the several views the same parts will be 35 found designated by the same numerals of reference.

Referring to Figs. 1 and 2, 1 is the top plate of the machine, 2 the roller-carriage, and 3 the platen-carrier, pivotally connected thereto in a manner common to the well-known 40 Remington No. 6 type-writing machine. The roller-carriage at near each end is provided with a forwardly-projecting vertical plate 4, to which is pivotally attached the lower end of a link or arm 5, whose upper end is pivotally attached to the rear of the platen carrier or frame 3 by suitable pins 6, also adapted to contact with either of two screw-stops 7 and 8, supported in ears at the upper end of the plate 4. The front side of the platen-carrier

frame is provided with a supporting-roller 9, 50 which travels upon a vibratory rail 10, attached to arms 10^a and adapted to be actuated by a shift-key (not shown) in the usual manner, whereby the platen-frame and its platen or roller 11 may be shifted for upper-case work. Normally the pins 6 rest against the screw-stops 8, at which time the platen is in position for printing lower-case characters; but when the shift-rail 10 is vibrated rearwardly the platen-carrier and 60 platen are moved in the same direction, and the pins are caused to strike against the stops 7, and at this time the platen is in position for printing upper-case characters, the type-bars having, as usual, each an upper 65 and lower case type. When the shift-key is released, spring mechanism returns the platen-carrier to its normal position, with the pins 6 against the front stops 8. The platen-carrier may be turned up about the hinge or 70 pivotal points 12 of its attachment to the links or arms 5 for inspection and correction of the work.

The roller-carriage comprises a horizontal top portion 13 and two vertically-depending 75 portions or members 14 and 15, the former being the longer of the two. 16 is a fixed rail for said carriage, secured to bracket 16^a, mounted on the top plate, and said rail has a horizontal bearing portion 17 and a vertical 80 bearing portion 18. The under surface of the top member 13 of the carriage forms or is provided with a bearing 19, which is opposite to and parallel with the bearing 17 on the rail, and the inner side of the depending 85 member 15 of the carriage forms or is provided with a bearing 20, which is opposite to and parallel with the bearing 18 on said rail. A vertically-disposed roll or disk 21 travels on the bearings 17 and 19, and a horizontally-disposed roll or disk 22 travels on the bearings 18 and 20. The rolls or disks 21 and 22 are arranged in pairs crosswise of each other, and there may be as many pairs as may be desired, two pairs being shown. Each 90 pair of rolls, as shown, is mounted in a holder 23, with the pivots of the rolls arranged at 95 right angles to each other, and these roll-

holders may be connected together, if desired, all as more fully set forth in my aforesaid first-filed application. It will be understood that said roll-holders are of such height 5 as to substantially fill the vertical space between the bearings or tracks 17 and 19, so that in case the roll-holders should not be connected together still the rollers or disks 22 would not sag appreciably toward the base 10 16; but said holders would rest upon the track 17, and therefore sustain the rollers 22 in substantially the position illustrated. At the ends of the rollway formed by the fixed rail and the carriage may be located stop-pins 24 15 to prevent the escape of the rolls. The rolls 21 sustain the vertical component of the weight of the carriage, and the rolls 22 and 28 support the turning moment. In other words, the carriage is hooked or hung upon the rolls 20 21, while the rolls 22 and 28 oppose its tendency to swing upon said rollers 21, and hence the forwardly-overhanging portion of said carriage is prevented from sagging or tipping. 25 To prevent the carriage from rising and 25 from tilting or rocking, it is provided with a flanged plate or finger 25, which may be secured to the member 14 by a screw 26, which finger or plate enters a slot or groove 27 in the other side of the fixed rail and travels 30 therein during the movements of the carriage, but without contacting with the surfaces thereof. The said plate or finger is, however, arranged very close to the sides of the slot or groove, so that it may immediately come in 35 contact therewith to prevent any tendency of the carriage to either rise or tilt or rock rearwardly. To prevent any forward rocking or tilting of the carriage, it is provided at its lower end with a horizontal wheel 28, (one or 40 more,) which travels on a bearing 29 on the lower front vertical face of the fixed rail 16. From the drawings and from the above description it will be seen that the weight of the carriage 2 and also the weight of the platen-carrier 3 when turned up are wholly sustained by the rolls 21; also, that the crosswise rolls 22, together with the roll or wheel 28, which may be mounted on a stud 30 on the carriage 2, guide the carriage laterally-- 45 50 that is, prevent vibrations of the carriage in a horizontal plane; also, that the wheel 28 and its track coöperate with the rolls 22 and the bearing-surfaces 18 and 20 to steady the carriage in a third direction--that is, to prevent 55 the carriage from rocking or tipping forwardly; also, that the plate or finger and the right-hand wall of the groove prevent the carriage from tilting rearwardly, and also that the said plate or finger and the base of 60 the said groove prevent the carriage from rising or from being lifted from the bearing-rail. When it may become necessary to detach the said carriage, the flange plate or finger is of course unscrewed and removed. The weight 65 of the rear portion of the hinged platen-carrier when down in working position, as shown

at Fig. 2, is also borne by the rolls 21, and the tendency of this weight to turn the upper portion of the roller-carriage forward is met and resisted by the crosswise wheel 28 bearing against its track 29. When the platen-carrier is shifted rearwardly violently against the stops 7, the tendency to turn or displace the roller-carriage is met and resisted by the plate or finger 25, and for the purpose of further obviating this tendency there may be arranged between the depending member 14 and the fixed rail a stop screw or device 31, (one or more,) which may be secured either to the fixed rail or to the carriage member 14. 80 Any violent forward shifting of the platen-carrier against the stop-screws 8, which would tend to tilt or displace the roller-carriage, is resisted by the horizontal rolls 22 and 28. 85 In the modification illustrated at Fig. 3 I have shown antifriction-balls 21^a and 28^a instead of rolls or disks, the lower ball or balls 28^a being arranged to travel in a V-shaped track 32 on the fixed rail and also on a beveled track or way 33 on the carriage member 14, whereby the ball is properly supported and prevented from dropping out. The balls 21^a preferably travel on plane bearings. The balls 21^a sustain the weight of the carriage, 95 as do the vertically-arranged rolls 21 in the other views, and the said balls 21^a also support or steady the carriage horizontally or laterally, as do the rolls 22 in the other views, while the ball or balls 28^a perform the function of the horizontal wheel 28 in Figs. 1 and 2. In other respects the construction exhibited in Fig. 3 is similar to that shown in the remaining views. 100

In the use of the term "roller-bearings" 105 herein I wish to include both the roll or disk form of Figs. 1 and 2 and the ball or spherical form of Fig. 3, although I prefer the former in practice.

What I claim as new, and desire to secure 110 by Letters Patent, is—

1. In a type-writing machine, the combination of the roller-bearing carriage 2, the platen-carrier 3 hinged or pivotally connected thereto, roller-bearings for supporting the vertical 115 component of the weight of the same, and additional rollers for supporting the turning moment of said weight and without adding to the pressure on the first-named supporting-rollers. 120

2. In a type-writing machine, the combination of the roller-bearing carriage 2, a platen-carrier hinged or pivotally connected thereto, roller-bearings for supporting the vertical 125 component of the weight of the same, and additional means for supporting the turning moment of said weight and without adding to the pressure on said roller-bearings.

3. In a type-writing machine, the combination of a roller-bearing carriage, a shifting platen-carrier pivotally connected or hinged thereto, roller-bearings for supporting the 130

vertical component of the weight of the same, and additional means for supporting the turning moment of said weight without adding to the pressure on said roller-bearings, and 5 means for holding the carriage in position when the carriage is shifted violently.

4. In a type-writing machine, the combination of a roller-bearing carriage, a shifting platen-carrier pivotally connected or hinged thereto, roller-bearings for preventing lateral vibration of said carriage and for supporting the weight of the same, and additional means for preventing said carriage from being lifted from its roller-bearings.

15 5. In a type-writing machine, the combination of a roller-bearing carriage, a shifting platen-carrier pivotally connected or hinged thereto, roller-bearings for sustaining the weight of the carriage, additional means for preventing said carriage from being lifted from its roller-bearings and additional means for preventing said carriage from turning when the platen-carrier is shifted violently.

6. In a type-writing machine, the combination of a roller-bearing carriage having a horizontal top and two depending vertical sides, a fixed track or way having a horizontal bearing and a vertical bearing, rolls or balls within the rectangular space formed by said top 20 and one of said sides and by the horizontal and vertical bearings of the fixed rail, a ball or roller for the other depending side of said carriage, and a fixed bearing therefor.

7. In a type-writing machine, the combination of a roller-bearing carriage having a horizontal top and two depending sides, a platen-carrier hinged or pivotally connected to said carriage, a fixed rail having adjacent bearings arranged at right angles to each other 30 and opposing the bearings formed by the under side of the said top and the inner face of one of said depending sides, rolls or balls arranged to contact with said bearings, a ball or roller for the other depending side of said carriage, and a fixed bearing therefor.

8. In a type-writing machine, the combination of a roller-bearing carriage having a horizontal top and two depending sides one of which is longer than the other, a platen-carrier hinged or pivotally connected to said carriage, a fixed rail having two bearing-faces opposing the bearing-faces formed by the under side of the top and the inner side of the shorter depending side of the carriage, rolls 50 or balls interposed between said bearings, and a ball or roller bearing for the longer depending side of said carriage.

9. In a type-writing machine, the combination of a roller-bearing carriage comprising a horizontal top and two depending sides, a fixed rail having a horizontal bearing and a vertical bearing, rolls or balls for said bearings and for the bearings formed by the said top and one of said sides, a roller attached to

the other one of said depending sides, and a 65 fixed bearing for said roller.

10. In a type-writing machine, the combination of a roller-bearing carriage comprising a horizontal top and two depending sides, a fixed rail having a horizontal bearing and a 70 vertical bearing, rolls or balls for said bearings and for the bearings formed by said top and one of said sides, a roller attached to the other one of said depending sides, a fixed bearing for said roller, and a platen-carrier 75 hinged or pivotally connected to said carriage.

11. In a type-writing machine, the combination of a roller-bearing carriage comprising the top 13, the two depending sides 14 and 15, the fixed rail having the bearings 17 and 80 18, the interposed rolls or balls, the bearings 29, the roll 28, the hook 25, and the groove in the fixed rail.

12. In a type-writing machine, the combination of a roller-bearing carriage comprising 85 a horizontal top and two depending sides, a shifting platen-carrier hinged or pivotally attached thereto, a fixed rail having bearings 17, 18 and 29 and the groove 27, the interposed pairs of rolls 20 22 arranged crosswise 90 of each other, the roll 28, and the hook 25.

13. In a type-writing machine, the combination of a carriage, a set of roller-tracks or bearing-surfaces, a set of rollers for sustaining the vertical component of the weight of 95 the carriage, and another set of crosswise rollers, as 22, 28 for preventing vibration of the carriage in a horizontal plane.

14. In a type-writing machine, the combination of a carriage, a set of roller tracks or 100 bearings, a set of rollers for sustaining the vertical component of the weight of the carriage, and a set of crosswise rollers, as 22, 28, for preventing the carriage from either vibrating in a horizontal plane or swinging 105 upon the first-mentioned set of rollers.

15. In a type-writing machine, the combination of a set of roller-tracks, a carriage overhanging forwardly of said tracks, a set of 110 rollers for sustaining said carriage, and a set of crosswise rollers for preventing either lateral vibration or tipping of said carriage.

16. In a type-writing machine, the combination of a set of tracks or bearing-surfaces, a carriage, rollers for sustaining said carriage, 115 and crosswise rollers for preventing lateral vibration of said carriage, each of said rollers being held in contact with its coacting track or bearing-surface by the weight of said carriage.

Signed at New York city, in the county of New York and State of New York, this 19th day of February, A. D. 1898.

GEORGE B. WEBB.
